[57] CLAIM

The ornamental design for a violin bow frog cover, as shown and described.

DESCRIPTION

FIG. 1 is a perspective view of a violin bow frog cover showing my new design;

FIG. 2 is top plan view thereof;

FIG. 3 is an elevational left side view thereof;

FIG. 4 is a front elevational view thereof;

FIG. 5 is a rear elevational view thereof;

FIG. 6 is an elevational right side view thereof; and,

FIG. 7 is a bottom plan view thereof.

The broken line showing of a bow is for illustrative purposes only and forms no part of the claimed design.
